UNITED STATES PATENT OFFICE

2,499,978

VOTING MACHINE

Ransom F. Shoup, Ardmore, Pa., assignor to The
Shoup Voting Machine Corporation, Philadelphia, Pa., a corporation of Delaware

Application August 20, 1947, Serial No. 769,719

2 Claims. (Cl. 235—54)

1

This invention relates to voting machines and more particularly to voting machines of the type disclosed in Shoup Patent No. 2,054,102.

In this type of voting machine, there are several vertical columns of voting spindles in combination with an interlock arranged normally to prevent actuation of more than one spindle in any horizontal row. Also, for each horizontal row of spindles there is a slot through which a personal choice may be written in, such slot being normally closed by a slide termed the personal choice slide. Each personal choice slide is connected to the interlock in such manner that opening of the personal choice slide prevents actuation of any of the spindles in the corresponding row, until after the machine has completed its vote-registering operation. Thus, if a voter actuates a personal choice slide and limits himself to a personal choice vote, he cannot vote for the regular nominee of any party except by writing in the name of such nominee as a personal choice vote. Heretofore, in this type of voting machine, it has been possible for a voter inadvertently to actuate a personal choice slide, thus depriving him of the right to actuate any of the spindles in the horizontal row of spindles corresponding to the actuated personal choice slide.

An object of this invention is a voter-releasable latch for the personal choice slides of such nature that the voter must release the latch before he can actuate any personal choice slide, thereby preventing the voter from inadvertently limiting himself to a personal choice vote for any particular office.

Other objects, novel features and advantages of this invention will become apparent from the following specification and accompanying drawings, wherein:

Fig. 1 is a fragmentary elevation of a Shoup type voting machine embodying the invention;

Fig. 2 is an enlarged partially broken away fragmentary view similar to Fig. 1;

Fig. 3 is a section on the line 3—3 of Fig. 2;

Fig. 4 is a section on the line 4—4 of Fig. 3, and

Fig. 5 is a section on the line 5—5 of Fig. 1.

In general, the reference characters used herein correspond as far as practical to the reference characters used in Shoup et al. Patent 2,054,102 and Shoup Patent 2,277,857.

Columns of spindles 38 are journaled at one end in vertical members 40, each spindle being equipped with an operating handle 30. A plate 39 supports columns of counters C associated with the spindles 38 and the structure of each counter

2

as well as the means for actuating the counter by the spindle is preferably the same as is disclosed in Shoup Patent 2,140,336. An interlock for the spindles comprises horizontal interlock straps 61 passing in pairs between pairs of interlock members 62 supported in longitudinal grooves in the inner faces of vertical channel member 42. Certain of the interlock members 62 are tubular and headed pins 63 extend through them and passages in the channel member to lock the tubular interlock members in fixed relation. Each interlock strap 61 is equipped at one end with an enlarged head or wedge 64 and each spindle 38 is equipped with a pair of arms 59 and 59' between which extends a pin 59b connected to an interlock strap 61.

In Fig. 5 is disclosed the spindle locking and restoring frame consisting of horizontal bars 65 connected by vertical channel straps 66 having cut-out portions providing rungs 67 arranged to engage the arms 59. The bars 65 are provided with an interconnecting track member 65b which engages rollers 65a carried by a vertical bar 68 supported for combined vertical and horizontal movement.

The bar 68 and the locking and restoring frame are shown in Fig. 5 in spindle-locking position. Horizontal movement of the bar 68 to the left from its Fig. 5 position releases the spindle locking and restoring frame for movement to the left into spindle-unlocking position and return movement of the bar 68 to its Fig. 5 position effects return of the spindle locking and restoring frame to spindle-locking position all as fully disclosed in Shoup, et al. Patent No. 2,054,102.

In the plate 39 is provided a vertical column of personal choice slots 139 with a closure slide 140 for each slot. In back of the slots 139 is a guide 141 over which passes a strip of paper 142 from a feed roller 143 to a take-up roller (not shown). A yoke 150 pivotally supported on a rod 150a is rotated counterclockwise from the position shown in Fig. 5 by movement of any slide 140 to open position and is returned to such position by mechanism (not shown) to advance the strip 142 a predetermined distance for each actuation of the yoke, all as disclosed in Shoup, et al. Patent 2,054,102.

A vertical plate 150c of the shape shown in Fig. 5 is provided with a vertical series of apertures constituting guideways for links 161 which, at one end, are attached to arms 160 pivotally supported by the rod 150a. Each link 161 is provided with a pin 161a connected to an interlock strap 61 and each arm 160 is provided with a

head 160a directed approximately perpendicular to the arm 160 in position to be engaged by a vertical plate 201 supported by the vertical bar 68. Each head 160a projects into a channel-shaped runner 222 slotted at 222a and having a right-angle extension attached to a plate 223 slidably supported by the plate 39 in alignment with a closure slide 140. Movement of any closure slide 140 from slot-closing position as shown in Fig. 5 to the left to slot-open position effects corresponding movement to the left of a plate 223 and through engagement of the runner 222 with the head 160a counterclockwise swinging movement of the arm 160 is effected from its Fig. 5 position to actuate the corresponding link 161 and the interlock strap 61 connected thereto. Return movement of the closure slide 140 by the voter to slot-closing position has no effect on the plate 223.

In the plate 39 is provided a slot 415 through which projects one arm 416 of a bell crank lever 417. A bracket 418 attached to the inner face of the plate 39 pivotally supports the bell crank lever 417 through the medium of a vertical pivot pin 419. As shown in Fig. 5, the arm 420 of the bell crank lever 417 projects across the inner face of the yoke 150 when the yoke is in its unactuated position, and is formed with a recess 421. In Figs. 2, 3 and 4, the yoke is assumed to be in its actuated position and so is not shown. Also, the end of the arm 420 is formed with an oblique surface 422. The recess 421 has straight parallel walls 423 and 424 spaced apart at a slightly greater distance than the width of the yoke 150 which the recess is adapted to receive. The wall 424 terminates in an inwardly projecting knob 425. A spring 426 normally biases the bell crank lever 417 clockwise.

With the voting machine in curtain-open position, the bell crank lever or latch 417 is in the position shown in Fig. 5 with the yoke 150 received in the recess 421 and the closure slides 140 are locked in slot-closing position by engagement of the heads 160a of the arms 160 with the plate 201. Upon movement of the machine into curtain-closed position, the plate 201 is moved to the left out of engagement with the heads 160a so that it no longer holds the closures 140 in slot-closing position. The closures 140, however, are still held in slot-closing position due to the fact that the yoke 150 is held against movement by the latch 417 and in this condition, no one of the personal choice slots can be opened. However, if a voter wishes to vote a personal choice, he pushes the arm 416 of the latch 417 to swing it counterclockwise (Fig. 5) thus moving the wall 423 out of the path of the yoke 150. Also, such movement of the latch causes the knob 425 to engage the yoke 150 to swing it counterclockwise a sufficient distance that its front edge overlaps the wall 423 so that the latch 417 cannot return to yoke-engaging position. Such movement of the yoke 150 does not, however, in any way produce any movement of any closure 140 but it does prevent the spring 426 from returning the yoke to locked condition upon release of the latch by the voter. After release of the yoke 150 as above described, the voter may actuate any of the per-

sonal choice slot closure slides 140 in the usual manner. Upon return of the machine to curtain-open condition, the yoke 150 is returned to its original position and during its return movement engages the oblique surface 422 of the arm 420 of the latch 417 to rotate the latch counterclockwise, thereby permitting the yoke 150 to be again received in the recess 421.

I claim:

10. In a voting machine, a plate having a slot, a plurality of personal choice slides, a pivoted yoke movable by any slide upon movement thereof from a closed to an open position, a bracket supported by said plate, a two-armed bell crank lever, a pivot securing said lever rotatively to said bracket with one arm extending through said slot for manipulation by a voter, the other arm of said lever having a recess to receive said yoke, said recess having straight parallel spaced-apart walls, one of said walls providing a shoulder for engagement with said yoke in a normal position of said lever to retain the yoke in a locked position to prevent movement of any slide from its closed to its open position, and a projection on said lever adjacent the other of said parallel walls, said projection acting upon rotation of said lever about said pivot out of the normal position of said lever to engage said yoke and to push said yoke out of position to be engaged by 20 said shoulder, thereby then freeing said yoke for movement by any of said slides.
2. In a voting machine, a plate having a slot, a plurality of personal choice slides, a pivoted yoke movable from a normal position by any slide 30 upon movement thereof from a closed to an open position, a bracket secured to said plate, a two-armed bell crank lever, a pivot securing said lever rotatively to said bracket with one arm of said lever extending outwardly through said slot in said plate for rotative manipulation of said lever by a voter, the second arm of said lever having a recess to receive said yoke in the normal position of the latter, said recess having spaced-apart parallel walls, a spring biasing said lever so that 40 in the said normal position of said yoke it lies in said recess of said second arm, one of said spaced-apart walls of said recess then acting to lock said yoke in its said normal position, a projection on said lever adjacent the other of said spaced-apart parallel walls, said projection acting upon rotative manipulation of said lever about said pivot by a voter in a direction counter to the biasing action of said spring to engage said yoke and to push the latter out of position 50 to be engaged by said shoulder, thereby freeing said yoke for movement by any of said slides.
